United States Patent Office.

C. K. MARSHALL, OF VICKSBURG, MISSISSIPPI.

Letters Patent No. 69,231, dated September 24, 1867.

IMPROVEMENT IN WINDOW-BLINDS.

The Schedule referred to in these Letters Patent and making part of the same.

TO ALL WHOM IT MAY CONCERN:

Be it known that I, C. K. MARSHALL, of Vicksburg, in the county of Warren, and State of Mississippi, have invented a new and useful Improvement in the Construction of Window-Blinds; and I do hereby declare that the following is a full, clear, and exact description thereof, which will enable others skilled in the art to make and use the same, reference being had to the accompanying drawings, forming part of this specification.

This improvement relates to a new article of manufacture, and consists in the construction of window-blinds with metallic slats. In the accompanying drawings—

Figure 1 is a front view of my improved window-blind, part of the frame being broken away to show the wood insertion in section.

Figure 2 is a transverse vertical section thereof; and

Figures 3 and 4 are vertical sections of alternative forms of slat.

Similar letters of reference indicate corresponding parts.

A A is a hollow frame of metal, in which are set the slats B B, either at a certain angle or revolving upon pivots *b*, or on an axis, *b*, passing through them and securing into the frame A. A piece of wood, C, is inserted in the hollow of the frame A, as shown in the drawing, fig. 1, to enable the hinges D to be secured thereto by the screws *d*, hinging the blind to the sash in the usual manner. When the slats are pivoted they are operated by the rod E, connecting with the slats by the link *e*, and fastening by the pin *f* of the piece F into the plate G. When it is not desired that the slats should open and close the form of an inverted V, shown in fig. 4, may be adopted.

The following are some of the advantages of my improvement: first, durability; second, protection against burglars; third, protection against the spread of fire; and, fourth, equal strength with better light and ventilation when substituted for the ordinary iron shutter.

Having thus described my invention, what I claim as new, and desire to secure by Letters Patent, is—

1. As a new article of manufacture, window-blinds formed of slats of metal set in a metallic frame, in manner and for the purposes substantially as described.

2. The hollow metal frame A, having the wooden blocks C to receive the screws *d*, securing the hinges D, in manner and for the purposes substantially as herein shown and described.

The above specification of my invention signed by me this 27th day of May, 1867.

C. K. MARSHALL.
